Primary Examiner — Cynthia Ramirez*(74) Attorney, Agent, or Firm* — J. Bennett Mullinax, LLC(57) **CLAIM**

The ornamental design for a transmission jack, as shown and described.

DESCRIPTION

FIG. 1 is a side perspective view of the transmission jack according to the present design;

FIG. 2 is a back view of the transmission jack as shown in FIG. 1;

FIG. 3 is a front view of the transmission jack as shown in FIG. 1;

FIG. 4 is a left side view of the transmission jack as shown in FIG. 1;

FIG. 5 is a right side view of the transmission jack as shown in FIG. 1;

FIG. 6 is a top view of the transmission jack as shown in FIG. 1; and,

FIG. 7 is a bottom view of the transmission jack as shown in FIG. 1.

The broken lines shown in FIGS. 1-7 are to show portions of the transmission jack which form no part of the claimed design.

1 Claim, 7 Drawing Sheets(56)
